UNITED STATES PATENT OFFICE.

EUGENE C. RICHARD, OF FLINT, MICHIGAN, ASSIGNOR TO GENERAL MOTORS CORPORATION, OF DETROIT, MICHIGAN, A CORPORATION OF DELAWARE.

VACUUM TANK.

Application filed December 29, 1922. Serial No. 609,720.

The present invention relates to vacuum tanks such as are used in supplying fuel for an internal combustion engine from a main tank located at a low level to a carburetor located at a high level.

One object of the invention is to provide a dump valve construction which may be readily removed as a unit through the bottom of the tank and without disturbing other elements thereof.

Another object is to provide an exceedingly simple, inexpensive and efficient valve mechanism whereby the application of suction to the vacuum chamber is controlled. 15 To this end, I avoid the use of snap mechanism and provide a light, simple valve for the suction passage arranged to snap to its seat by suction and entirely shut off the suction independent of the float action.

20 The invention is also concerned with certain details of construction hereinafter more fully described and claimed.

Referring now to the drawings accompanying and forming a part of this specification, wherein a preferred embodiment of the invention is illustrated:

Fig. 1 is a diagrammatic view showing the relation of the tank to the usual intake manifold and carburetor;

Fig. 2 is an enlarged vertical section taken on line 2—2 of Fig. 1 showing a preferred embodiment of the invention;

Fig. 3 is a section at right angles to Fig. 2, parts being broken away;

Fig. 4 is a plan view corresponding to Fig. 2, parts being broken away;

Fig. 5 is a fragmentary view of the valves showing the suction port open and the vent closed;

Fig. 6 is a view corresponding to Fig. 5 showing both ports open; and

Fig. 7 is a view corresponding to Fig. 5 showing the suction port closed and the vent open.

45 On the drawings, the reference character 1 indicates the usual engine intake manifold to which the carburetor 2, embodying a float chamber 3, is connected through a mixture passage controlled by a throttle 4. The pipe 5 whereby suction is communicated to the vacuum chamber appears at 6; the pipe through which fuel is lifted to the vacuum chamber from the low level tank 6 (usually located at the rear of the vehicle) is seen at

7; and liquid flows from the vacuum tank 55 through the pipe 8 to the carburetor.

The actual construction of the tank may be varied within wide limits. As shown, it embodies a shell 17 having a vacuum chamber 10 and an auxiliary or receiving chamber 11 to which fuel is delivered from the chamber 10 through a passage 12 formed in a valve fitting 13. The latter is provided at its lower end with a valve 14, preferably of the normally open type, and has at its 60 upper end a centrally perforated plate or spider 15 adapted to receive the float guide rod 16. Connection to the diaphragm 20, whereby the chambers 10 and 11 are separated, is made by means of the threaded annular member 21 preferably soldered to the diaphragm, and having the depending flange 22 upon which the tapered surface 23 of the fitting 13 is adapted to bear to form a tight 65 seal.

In order that the fitting 13 may be readily assembled, removed or inspected, I provide the bottom 25 of the receiving chamber with a threaded reinforcing member 26 which is soldered thereto. Fitting the reinforcing member is a threaded plug 27 having an opening 28 aligned with the opening in the member 21, and arranged to receive the pipe 8 leading to the float chamber 3 of the carburetor. This manner of assembly 70 and removal I regard as broadly new.

The cap or cover for the vacuum chamber may vary in construction, but preferably comprises a body 30 attached by screws 31 to the rest of the tank. An outer member 32 and an inner member 33 are secured to the cover 30, either of which may pass through the opening 34 in the cover. In the construction shown, the outer member 32 passes through the opening 34 and is threaded as 75 at 35 to receive the other member and to clamp the several parts together. The outer member is provided with the suction passage 36 with which the pipe 5 communicates, said passage terminating in the valve chamber or opening 37. The valve 38, which may be in the form of a ball, serves to alternately open and close the suction passage 36, said valve being operated, in the construction shown, by a sliding link 39 connected to the float 40 and extending upwardly therefrom. The valve has an upper guide 41 and a lower guide 42, said lower guide loosely 80 85 90 95 100 105 110

fitting an aperture 43 in the inner member 33. The valve may be mounted and have its guides in the cover 30, but as stated heretofore and for the convenience of assembly, the cap or cover is shown as made in three parts.

Within the outer member 32 and adjacent the suction port 36 is an air or vent valve 44 having an extension 45 which is adapted to seat on an annular disc 46 on the valve 38. This valve when open breaks the vacuum in the chamber 10, thus the chamber is under atmospheric pressure by means of the passage 47-48-49. The chamber 10 is also adapted to be put in communication with the chamber 11 for equalizing the pressure in the two chambers by means of the passage 50-51-52 and the chamber for the valve 44. The two ports for the suction valve and vent valve leading into the suction chamber have their axes in parallel alignment, which simplifies the machining operation.

In operation, assuming that the tank is empty, the float being at the bottom of the chamber 10, the suction valve will be open and the vent closed as shown in Figure 5. If suction is applied through the passage 36, gasoline will be drawn from the tank 6 through the pipe 7 and opening 55 into the chamber 10. The gasoline will raise the float and suction valve by means of the upwardly extending link 39 which engages a shoulder 56 on the valve 38 and is adapted to slide along the guide 42. This link is extended upwardly to reduce the length of the valve guide and consequently the weight which is very desirable. When the largest section of the suction valve enters the passage 37, as shown in Figure 6, the valve disc 38 has opened the vent valve. In this position the valve is balanced and could not raise any further if the inflow of gasoline were to stop, but the moment the valve disc breaks the vent valve off its seat, air rushes in the chamber, unbalancing the suction valve which will at once jump to its seat as shown in Figure 7 because of the dynamic upward pressure on the valve caused by the air velocity at the passage 37, the passage at this point being restricted so that the velocity is greater than at any point in the suction line.

Thus it will be understood that the valve has a snap action on its seat, independent of the float and any snap mechanism. First the suction is partially closed, then the vent is opened by the action of the float, and then the suction is entirely shut off independent of the float, the three being successive to each other. The two chambers 10 and 11 are now under atmospheric pressure and the liquid flows through the perforated plate 15 and passage 12 to the chamber 11. As the float lowers with the liquid level, the link 39 slides down the valve guide 42 engaging the shoulder 58, thereby breaking the suc-

tion valve off its seat and allowing the vent valve to partially close. The air velocity in the passage 47 then positively closes the vent valve and the extension 45 forces the suction valve away from its seat after the float has initially moved the same. The vent valve, as well as the suction valve, is thus positively closed and opened independent of the float action. The initial movement of the float in either direction partially opens and closes the vent and suction valves, and the velocity of air passing through the openings completes the movements of said valves, causing them to open and close with a snap action. It will be noted that as the suction valve 38 approaches its seat the air passage 37 becomes more and more restricted while the vent passage 47 is progressively increasing and becomes less restricted, which allows the vent valve 44 to have a free upward movement, while the suction valve is materially hastened to its seat.

When the suction valve 38 is initially opened by the float, the action of the valves is reversed and the passage 47 is more and more restricted, snapping the vent valve 44 to its seat, while the passage 37 is progressively increasing and becomes less restricted, causing the valve 38 to have a free downward movement and to remain in the open position. When the shoulder 58 reaches the member 33 it forms a stop for the suction valve 38 and limits its downward movement.

It is understood that this invention is not limited in its application to the particular construction herein illustrated, as various changes might be made in the construction shown without departing from the spirit of this invention as set forth in the appended claims.

I claim:

1. In an internal combustion engine fuel feeding system of the vacuum type, a shell having a diaphragm separating said shell to form a suction chamber and a receiving chamber, a threaded annular member secured to said diaphragm, a fitting threaded at its upper end to engage said annular member, a tapered surface on one of said members to engage a flange on the other member to form a seal, a threaded reinforcing member secured to said receiving chamber, a threaded plug having a diameter greater than that of said fitting and adapted to engage said reinforcing member, whereby when said plug is removed said fitting may be removed through the opening in said reinforcing member.

2. In an internal combustion engine fuel feeding system of the vacuum type, a shell having a pair of chambers, one of said chambers having a suction passage and a vent passage leading thereto, and the other a receiving chamber having a vent passage and

an outlet passage, a movable float in said suction chamber, a valve at the open end of said suction passage and having a guide within said suction passage, an upwardly extending link secured to said float and engaging a lower guide on said suction valve, a vent valve having its port in parallel alignment with the port of said suction valve, said vent valve located in the vent passage and extending through the port of said passage and adapted to engage said suction valve.

3. A vacuum tank comprising a suction chamber having a downwardly opening passage for exhausting air therefrom, said passage terminating in a cylindrical portion emerging at its upper end into a conical valve seat, a float within said chamber, a valve of light weight for said seat having movement into and away from said cylindrical portion, said valve including a stem, means whereby said stem is loosely guided at both top and bottom, and a link connected to the float and loosely surrounding the stem between the points at which it is guided whereby the major portion of the travel of the float is permitted without moving the valve, the float, when near the upper end of its travel, lifting the valve into said cylinder.

drical portion of said passage whereupon the valve is drawn suddenly to its seat by unbalanced air forces.

4. A vacuum tank comprising a float chamber, a float therein, a suction passage leading into the upper part of said chamber, a valve movable toward and from said passage, said valve having a short stem depending therefrom, and a link carried by said float and extending upwardly therefrom and having limited movement along said stem and cooperating therewith to draw said valve away from said passage when the float reaches a predetermined low level.

5. In an internal combustion engine fuel feeding system of the vacuum type, a shell having a vacuum chamber and a receiving chamber, a cover for said vacuum chamber, an outer member and an inner member secured to said cover, one of said members adapted to pass through an opening in said cover being provided with a suction valve and a vent valve, the other member forming a guide for said suction valve and engaging said first mentioned member.

In testimony whereof I affix my signature.

EUGENE C. RICHARD.
